UNITED STATES PATENT OFFICE.

WILLIAM P. CRARY, OF NEW YORK, N. Y.

DESIGN FOR A LAMP-BODY.

SPECIFICATION forming part of Design No. 34,176, dated March 5, 1901.

Application filed January 24, 1900. Serial No. 2,687. Term of patent 7 years.

To all whom it may concern:

Be it known that I, WILLIAM P. CRARY, a citizen of the United States, residing in the city of New York, borough of Manhattan, in the county and State of New York, have invented and produced a certain new and original Design for a Lamp-Body, of which the following is a full, clear, and exact specification, reference being had to the accompanying drawings, forming part thereof.

Figure 1 is a perspective view of the lamp-body as seen from the front, and Fig. 2 is a corresponding rear view. Fig. 3 is a side elevation.

The leading features of my design are the cylindrical base, the spheroidal portion thereon having a concave front face and the flared extension joining it to the base, and the parabolic front portion seated in the said concave front face.

The cylindrical base A is ornamented with alternate beads and bands A² A³, and the

spheroidal upper portion B has a central encircling bead B' and bands B². The front face B³ is concave, as shown, and receives the convex rear portion of the parabolic front C, which is ornamented by the beads C' C² and jewel C³ and is surmounted with an ornamental upwardly-projecting cap or chimney D.

The curved rear portion of the parabolic front seated in the concave front face of the spheroidal portion forms a pleasing and distinctive feature of the design, and the whole is well proportioned and attractive.

I claim—

The design for a lamp-body herein shown and described.

In testimony that I claim the design above set forth I affix my signature in the presence of two witnesses.

WILLIAM P. CRARY.

Witnesses:

CHARLES R. SEARLE,
HARRY E. CARRINGTON.
